UNITED STATES PATENT OFFICE.

REGINALD A. FESSENDEN, OF FORTRESS MONROE, VIRGINIA, ASSIGNOR, BY DIRECT AND MESNE ASSIGNMENTS, TO THE NATIONAL ELECTRIC SIGNALING COMPANY, OF PITTSBURG, PENNSYLVANIA, A CORPORATION OF NEW JERSEY.

SIGNALING BY ELECTROMAGNETIC WAVES.

1,002,049.

Specification of Letters Patent. Patented Aug. 29, 1911.

Application filed August 8, 1903. Serial No. 168,797.

To all whom it may concern:

Be it known that I, REGINALD A. FESSENDEN, residing at Fortress Monroe, in the county of Elizabeth City and State of Virginia, a citizen of the United States, have invented or discovered certain new and useful Improvements in Signaling by Electromagnetic Waves, of which improvements the following is a specification.

10 My invention relates to selective signaling in systems where the signal is transmitted by impulses or waves, and its primary object is to neutralize any disturbing impulses or waves, that is any not having the 15 periodicity of those waves or impulses which it is desired to receive.

Figure 1 in the accompanying drawing forming a part of this specification shows a 20 diagrammatic view of a form of apparatus adapted to the practice of my invention. Fig. 2 shows a similar view where the aerials are grounded. Figs. 3 and 4 are diagrammatic views illustrating modifications of my improvement.

25 In the practice of my invention I employ two or more conductors 6 and 7, which are tuned to different periodicities by any suitable means, as by the wires or coils 8 and 9, which connect the conductors to a coherer 10 or other suitable wave responsive device. 30 Each of the wires or coils 8 and 9 is preferably of approximately the same length as the conductor to which it is connected.

35 A grounding of the receiving conductors is not necessary, as efficient receiving can be effected without a ground. A suitable construction where a ground is used is shown in Fig. 2, where 6 and 7 are the aerials, 8 and 9 primaries of transformers, whose 40 secondaries 16 and 17 are arranged to act upon the receiver 10. A condenser 13 may be used as shown.

45 When employing a coherer it is connected as usual in the circuit of a battery 11, Fig. 1, or 1, Fig. 2, and with a relay or transmitting mechanism, 12, Fig. 1, or 15, Fig. 2. In the construction here shown the wave responsive device is affected by waves of either of the periodicities to which the receiving 50 conductors 6 and 7 are tuned, or to both periodicities conjointly, provided that the oscillations are sufficiently prolonged. The wave responsive device may be adjusted by varying its sensibility so as to respond

only when the effect of both the aerials is 55 added and not to the effect produced by a single one, in which case the wave responsive device will only be operated by the conjoint action of the two sets of waves.

When an electric impulse is received by 60 the conductors 6 and 7, the first few oscillations of the series of waves will generate nearly the same potential at the ends of the coherer or translating device 10, Fig. 1. But if the oscillations persist, and their 65 periodicity agrees with that to which either of the receiving conductors is tuned, the potential at one end of the coherer will rise higher than that of the other and the receiver will be actuated. If, however, the 70 periodicity of the impulse does not agree with that to which either receiving conductor is tuned, there will be no cumulative rise in the potential at one end of the receiving device, and if the periodicity of the impulse 75 be sufficiently different from the periodicities to which the receiving conductors are tuned, there will be no appreciable rise at one end above that of the opposite end.

As the coherer or other translating device 80 is so constructed as to be unresponsive to approximately equal potentials, or the potentials so nearly neutralize each other as to produce no operative effect on the coherer or wave responsive device, it follows that 85 the apparatus at any receiving station will not respond to any wave or series of waves or impulses which will not produce or generate at the coherer or other wave responsive device potentials differing to a predetermined degree. Thus disturbing impulses of 90 a frequency different from that which it is desired to receive produced by other stations or by atmospheric disturbances will be 95 unable to affect the receiver.

It is preferred that the aerials 6 and 7 should be of approximately the same height, i. e., should not differ more than a few per cent.

Where this invention is used for wire 100 lines, as telegraph lines or cables, the conductors 6 and 7 are preferably connected to each other above the coils 8, 9, and the junction connected to the line wire 14, as shown in Fig. 3. In this case condensers 105 13 are preferably placed in series with each of the conductors 6 and 7 also, instead of grounding the conductors 6 and 7, they may

be connected to a return conductor. Instead of a coherer a cumulatively acting receiver, of the current operated type, as a barretter is preferably used.

By receiving conductor I mean the entire circuit including the antenna and to ground.

What I claim as my invention:

1. In a system of signaling, a conductor for leading the received impulses into the receiving station, two circuit elements operatively connected to said conductor, and a circuit containing a receiver, operatively connected to said circuit elements in such a manner that said circuit elements produce voltages approximately equal but opposite in sign in the circuit containing the receiver, on the receipt of disturbing impulses, and voltages differing in magnitude on the receipt of the desired impulses.
2. In a system of signaling, a conductor for leading the received impulses into the receiving station, two circuit elements operatively connected to said conductor and a circuit containing a receiver inductively connected to said circuit elements in such a manner that said circuit elements produce inductively voltages approximately equal but opposite in sign in the circuit containing the receiver, on the receipt of disturbing impulses, and voltages differing in magnitude on the receipt of the desired impulses.
3. In a signaling system, a conductor for leading the received impulses into the receiving station; two transformers having their primaries connected to the leading in conductor, and a receiver operatively con-

nected to the secondaries of the transformers.

4. In a system of signaling by periodic impulses a conductor for leading received impulses into the receiving station, two transformers having their primaries in parallel with each other and operatively connected to the leading in conductor and a condenser in series with each of the primaries of the transformers, and the secondaries of the transformers operatively connected to each other and to a receiver, in such a manner that they oppose and neutralize the effect on the receiver of disturbing impulses, while the effect of impulses of the desired frequency is transmitted to the receiver in practically full strength.

5. In a system of wireless signaling, the combination of an antenna, a receiver and two circuits having suitable electric constants and suitably arranged to neutralize the effect on the receiver of disturbing impulses received from any direction.

6. The combination of two antennæ of approximately equal height but of different natural periods, a circuit containing a receiver inductively connected with both antennæ and arranged to be responsive only to a particular frequency of waves received on the said antennæ, substantially as described.

In testimony whereof, I have hereto set my hand.

REGINALD A. FESSENDEN.
